CONSOLE TABLE

Gordon L. Duern and Donald S. Griffin, Kitchener,
Ontario, Canada, assignors to Electrohome Limited,
Kitchener, Ontario, Canada

Filed Mar. 26, 1971, Ser. No. 128,643

Term of patent 14 years

Int. Cl. D6—03

U.S. Cl. D6—79

FIG. 1 is a perspective view of a console table showing our design, taken from the front and to one side, looking down obliquely; and

FIG. 2 is a perspective view of the console table of FIG. 1, taken from the opposite point in space looking up obliquely and showing the portions not visible in FIG. 1.

We claim:

The ornamental design for a console table, as shown.
